STORAGE BUNKERS

George Boswinkle, St. Joseph, Mich., Donald A. Nordal, Scottsdale, Ariz., and William F. Saenger, St. Joseph, Mich., assignors to Whirlpool Corporation, a corporation of Delaware

Filed Jan. 19, 1962, Ser. No. 167,257
5 Claims. (Cl. 312—248)

This invention relates to storage apparatus particularly of a weight conserving type for use in space vehicles and the like.

In space vehicles it is of course necessary that the weight be kept to a minimum and that the living quarters for the occupants of the vehicle be as compact as possible. In addition, it is necessary that these quarters be self-contained and capable of functioning under conditions of substantially no gravity, normal gravity and forces of several times gravity. This of course raises serious problems in storage cabinets or bunkers that will retain and maintain supplies necessary for the life and comfort of the occupants of the living quarters of the space vehicle.

The present invention is concerned with this problem of providing proper storage. Thus, one of the features of this invention is to provide improved storage means that will maintain stored supplies safely and securely under all normal conditions of weight ranging from substantially no weight at all through normal weight or gravity to forces equal to several times gravity.

Other features and advantages of the invention will be apparent from the following description of one embodiment thereof taken in conjunction with the accompanying drawings. Of the drawings:

FIGURE 1 is a perspective view broken away for clarity of illustration of a portion of the living space within a space vehicle and illustrating a kitchen or food storage and preparation center.

FIGURE 2 is a front elevational view of the space kitchen with portions removed for clarity of illustration.

FIGURE 3 is a plan view partially broken away of the storage cupboards of FIGURES 1 and 2.

FIGURE 4 is a sectional view taken substantially along line 4—4 of FIGURE 3.

FIGURE 5 is a sectional view taken substantially along line 5—5 of FIGURE 4.

FIGURE 6 is a sectional view taken substantially along line 6—6 of FIGURE 3.

FIGURE 7 is a sectional view taken substantially along line 7—7 of FIGURE 3.

FIGURE 8 is a fragmentary sectional view taken substantially along line 8—8 of FIGURE 6.

In the exemplary embodiment of the invention as disclosed in the drawings, a space kitchen generally designated 10 is shown as installed in a tubular shell 11 which may comprise a portion of a space vehicle arranged to carry human passengers. As such a space vehicle encounters different gravitational conditions including zero gravity conditions, the kitchen 10 is arranged for effective operation under any one of such different gravitational conditions. The kitchen 10 includes an oven generally designated 12 for heating packaged products such as precooked foods in suitable storage containers. Food storage facilities are provided in the kitchen 10 in the form of freezer 14, refrigerator 15 and bunkers 20. The kitchen is arranged to store sufficient food to maintain three men for a period of several weeks in space. The oven 12 is arranged to warm concurrently sufficient food-stuffs to comprise a meal for one man. This person utilizes the oven 12 while standing or sitting at a counter 17 spaced subjacent the oven. As best seen in FIGURE 2, the person standing or sitting at counter 17 has the

2

oven 12 disposed immediately in front of him with the freezer 14 and refrigerator 15 conveniently located at his left and right hands respectively. In addition, water supply means 18 is immediately disposed to the left of refrigerator 15 and a waste bunker 19 is provided below the refrigerator 15.

As can be noted from FIGURES 1 and 2, there are 10 elevated storage bunkers 20 aligned at the top of the kitchen 10. For convenience these are numbered in FIGURE 2 from 1 to 10. All of the bunkers are rotatably mounted on a circular pipe 21 held by spaced clamps 22 that are fastened to the forward ends of forwardly extending hangers 23. These hangers are located at the ends of the assembly of bunkers 1—10 and between groups of bunkers as illustrated in FIGURE 5. The rear ends of these hangers 23 are bolted to structural members 24 that form part of the framework of the space vehicle. As shown in FIGURE 3 other structural members 25 are located rearwardly of the members 24.

As can be seen from the drawings and particularly FIGURE 4 which illustrates an end bunker No. 10, an interior wall 26 forms a support means for the bunkers. The second support means is the horizontal pipe 21 and under normal gravity conditions the center of gravity of the bunkers is inwardly of the pipe 21 and toward the wall 26. In addition to the wall 26 constituting the first support means and the pipe 21 constituting the second support means, there is provided a third support means here shown as latches 27 normally engaging holders 28 attached to the wall 26. The latches 27 are primarily intended to cooperate with the first and second support means to retain the bunkers in storage position when under conditions of no gravity or weightlessness.

The bunkers 20 are provided on their forward surfaces with handles 29 which are aligned as illustrated in FIGURES 1 and 2 and being elevated operate as hand holds for a man working at the kitchen 10. When the bunkers 20 are to be moved to positions of access individually, the latch 27 on the desired bunker may be opened and the individual bunker rotated forwardly about the pipe 21 to a position of access as shown by dotted lines in FIGURE 4. In this position the individual bunker rests against a bumper strip 30 mounted on a series of hangers 31 similar to the hangers 23 with these hangers 31 being bolted or otherwise attached to a structural member portion 32.

Each of the bunkers 20 is provided with interior holding means for retaining stored supplies such as food and other supplies essential to the comfort and well being of the occupants. In addition, the two end bunkers Nos. 1 and 10 are provided with air passages therein to aid in the movement of air in the interior of the space ship. Positive air moving means such as blowers (not shown) are mounted beneath the freezer 14 and refrigerator 15 to move air over the heat dissipating portions of the refrigeration components of the freezer and refrigerator. These refrigeration components may include thermoelectric elements and thus air must be passed over the heat radiating fins associated with said elements for maximum performance. The air is drawn inwardly by the air moving means through the air passages in end bunkers Nos. 1 and 10, passed over the refrigeration components, and outwardly near the floor of the kitchen.

As is shown in FIGURES 4 and 5, one end bunker No. 10 is provided with a transverse horizontal partition 33 above the bottom thereof to provide a space 34. Air openings at the front of this space are provided by an expanded aluminum grill 35 having holes therein for the passage of air. The rear 34a of this space is open so that the rear of the space communicates with spaces behind the refrigerator 15 in connection with the one end bunker

No. 10 and the freezer 14 in connection with the first end bunker No. 1 for passage of air as described above. The two end bunkers are constructed similarly.

In order to simplify the drawings, stored articles within the bunkers are not shown. However, the storage means for certain illustrative bunkers are shown. Thus, in each of the end bunkers, as exemplified by the one end bunker of FIGURE 4, there is provided above the partition 33 a plurality of vertically extending aluminum sheets 36 arranged parallel to each other and having their lower ends attached to the aluminum partition 33 and their upper ends attached to a curved upper aluminum sheet 37 that follows the curvature of the curved wall 26 but is spaced inwardly thereof to provide an air space. These vertical aluminum sheets 36 are slotted as illustrated in FIGURE 5 with one set of slots in all the sheets being horizontally aligned. Each horizontally aligned section of slots is adapted to hold a plastic sheet 38 which may be linear polyethylene. An exemplary thickness of these sheets is about 0.032 inch. Stored articles are intended to be placed on these sheets 38 and be held in place not only by the vertically extending aluminum sheets 36 but also by spaced elastic cords 39 of the type illustrated in FIGURES 6 and 7 in connection with bunker No. 7. The front of each bunker as illustrated in FIGURE 4 is a solid sheet 40 of aluminum.

Each of the bunkers 20 rotates on the pipe 21 about a sleeve bearing 41, as illustrated in FIGURE 5, and this bearing may be of nylon or the like. A typical intermediate bunker No. 7 is illustrated in partially broken away plan view in FIGURE 3 and the opposite sides are shown in sectional elevations in FIGURES 6 and 7. As is shown in FIGURE 6 the left-hand side of this typical bunker, as viewed in FIGURES 1, 2 and 3 is provided with vertical sheets of aluminum 42 having their opposite ends connected to the curved top 43 and horizontal bottom 44a aluminum sheets of the bunker. The front of the bunker comprises a vertical aluminum sheet 44 at the top and a downwardly and rearwardly sloped aluminum sheet 45 at the bottom. Thus, each bunker is completely enclosed at the top, front and bottom. The vertically spaced and parallel sheets 42 of aluminum are slotted so as to provide horizontally aligned slots in the assembly of vertical sheets. Each aligned set of slots retains a plastic sheet 46 that is similar to the plastic sheets 38 previously described. Then, the sides of the bunker are provided with vertical elastic cords 47 which may be made of rubber or the like with the upper ends of the cords being held in L-shaped brackets 48 attached to the curved aluminum sheet top 43 and the lower ends of the cords being attached to flanges 49. The assembly of vertical cords 47 are located on opposite sides of the bunkers and may be displaced when the bunker is in forward access position to insert and remove stored articles.

As shown in FIGURE 3 the bunker No. 7 is divided into the two parts by a vertical aluminum sheet 50. As previously explained, on one side of the sheet are located the vertical aluminum sheets 42, horizontal plastic sheets 46 and the one set of side elastic cords 47. On the opposite side of the dividing sheet 50 a different type of holding means is provided. This holding means comprises vertical corrugated aluminum sheets 51 having their tops and bottoms attached in the same manner as the sheets 42 with spaced substantially horizontal wires 52 extending through and attached to the corrugated aluminum sheets 51. These wires serve to retain in position stored articles such as paper packets which are of slightly greater width than the minimum opening between the corrugated sheets 51. This side of the bunker is also provided with a set of vertical elastic cords 47. These cords retain the several packets and packages stored within the bunkers when the bunkers are open under zero gravity conditions.

As best shown in FIGURES 3, 4 and 5, guide-angles 54 and guide-T's 55 are secured to the interior wall 26.

These guide members guide the rotation of the bunkers as they are rotated from the closed to open positions. In addition these guide members 54 and 55 provide load bearing support for the bunkers under the extreme thrusts imposed in a longitudinal direction as in blasting off or decelerating to land.

As can be seen, the space kitchen including the storage bunkers provides maximum accommodation for the smallest amount of space. The weight is kept to a minimum not only by using lightweight metals such as aluminum alloys but also by providing simplified supporting means which include the wall means of the interior living space as well as a second support means for retaining the bunkers in position under gravity conditions and a third support means which assists in retaining the bunkers in position even under conditions of little or no weight. In addition, the bunkers are so constructed that when they are in storage position they are automatically closed to prevent accidental dislodgment of stored articles. Then, when each bunker, as desired, is moved to access position the articles may be easily removed such as by displacing holding means exemplified by the elastic cords of the illustrated embodiment.

Having described our invention as related to the embodiment shown in the accompanying drawings, it is our intention that the invention be not limited by any of the details of description, unless otherwise specified, but rather be construed broadly within its spirit and scope as set out in the accompanying claims.

The embodiment of the invention in which an exclusive property or privilege is claimed is defined as follows:

1. Storage apparatus for a space vehicle and the like having interior wall means, comprising: a plurality of storage units movable from and toward storage position adjacent said wall means; support means for said units; and means in one of said units forming a first ventilating passage having one end communicating with a space adjacent said wall means and an opposite end communicating with a space inwardly of said wall means and storage units when said one unit is in the storage position, said support means being arranged to space said one unit from said interior wall means to provide a second ventilating passage therebetween when said one unit is moved away from said storage position.

2. Storage apparatus for a space vehicle and the like having interior wall means and means forming a living space inwardly of said wall means, comprising: a plurality of storage units movable from and toward storage position adjacent said wall means; support means for said units; additional apparatus beneath said storage units adjacent but spaced from said wall means; and means in one of said units forming a first ventilating passage extending from said living space, through said unit to the space between said interior wall means and said additional apparatus when said one unit is in the storage position, said support means being arranged to space said one unit from said interior wall means to provide a second ventilating passage therebetween when said one unit is moved away from said storage position.

3. Weight conserving storage apparatus for a space vehicle and the like having interior wall means, comprising: a plurality of storage units movable from and toward storage position adjacent said wall means; a fixed member on which said units are rotatable from said wall means and thus said storage position toward an access position, the center of gravity of said units being located between said fixed member and said wall means when said units are in said storage position; additional apparatus beneath said storage units adjacent but spaced from said wall means; means in one of said units forming a ventilating passage extending through said unit to the space between said interior wall means and said additional apparatus; and means in said one unit above said ventilating passage forming an article storage section.

4. Weight conserving storage apparatus for a space

vehicle and the like having interior wall means, comprising: a plurality of storage units movable from and toward storage position adjacent said wall means, said storage units being aligned and including a pair of end units; support means for said units; additional apparatus beneath said storage units adjacent but spaced from said interior wall means; means in each of said end units forming a ventilating passage extending through said unit to the space between said interior wall means and said additional apparatus, and means in each of said end units above said ventilating passage forming an article storage section.

5. Weight conserving storage apparatus for a space vehicle and the like having interior wall means, comprising: a plurality of storage units movable from and toward storage position, said storage units being aligned and including a pair of end units; a plurality of cooperating support means for said units one of which comprises said wall means, a second of which constitutes a support under gravity conditions and a third of which constitutes a support under substantially zero gravity conditions, said sec-

ond support means comprising a fixed member on which said units are rotatable from said wall means and thus said storage position toward an access position, the center of gravity of said units being located between said fixed member and said wall means when said units are in said storage position; additional apparatus beneath said storage units adjacent but spaced from said interior wall means; means in each of said end units forming a ventilating passage extending through said units to the space between said interior wall means and said additional apparatus; means in each of said end units above said ventilating passage forming an article storage section; and means in each of said storage units and said storage sections for retaining stored articles regardless of gravity conditions.
